CLAIM

The ornamental design for a pair of left and right brachytherapy ovoids, as shown and described.

DESCRIPTION

FIG. 1 is a front right perspective view of a pair of left and right brachytherapy ovoids showing a first embodiment of my new design;

FIG. 2 is a rear left perspective view thereof;

FIG. 3 is a front elevation view thereof;

FIG. 4 is a rear elevation view thereof;

FIG. 5 is a right side view thereof;

FIG. 6 is a left side view thereof;

FIG. 7 is a top plan view thereof;

FIG. 8 is a bottom view thereof;

FIG. 9 is a front left perspective view of a pair of left and right brachytherapy ovoids showing the first embodiment of my new design;

FIG. 10 is a rear right perspective view of FIG. 9;

FIG. 11 is a front elevation view of FIG. 9;

FIG. 12 is a rear elevation view of FIG. 9;

FIG. 13 is a left side view of FIG. 9;

FIG. 14 is a right side view of FIG. 9;

FIG. 15 is a top view of FIG. 9; and,

FIG. 16 is a bottom view of FIG. 9.

The broken lines shown in the drawings illustrate portions of the pair of left and right brachytherapy ovoids that form no part of the claimed design.

1 Claim, 8 Drawing Sheets
